UNITED STATES PATENT OFFICE.

CORNELIUS YOUNG, OF SANDY HILL, NEW YORK, ASSIGNOR OF ONE-HALF
TO HOWLAND & CO., OF SAME PLACE.

STUFF-REGULATOR FOR PAPER-MACHINES.

SPECIFICATION forming part of Letters Patent No. 276,127, dated April 17, 1883.

Application filed March 15, 1883. (No model.)

To all whom it may concern:

Be it known that I, CORNELIUS YOUNG, a citizen of the United States, of Sandy Hill, in the county of Washington and State of New York, have invented certain new and useful Improvements in Stuff-Regulators for Paper-Machines; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in paper-machines; and the objects of my invention are to regulate the flow of pulp or stuff from the stuff-box to the machine proper, and to provide a convenient means of wholly discharging the contents of the stuff-box.

My invention consists of an improved float and mechanism through which it acts upon a gate to regulate the stuff-supply; also, of an improved gate adjustable upon a sliding support, and of another gate to discharge the stuff from the stuff-box when it is desired to empty the same; also, of an improvement in the stuff-box, which consists in constructing the stuff-compartment narrower on the inside at one end or side, and placing the outlet on that side.

Figure 1 is a perspective view of a stuff-box, showing my improvements. Fig. 2 is a vertical section taken at broken line *a b* in Fig. 1. Fig. 3 is a perspective of the discharge-gate. Figs. 2 and 3 are on Sheet 2.

A is a box divided into three compartments by the partition B, which runs from one side of the box to the opposite side, and the partition C, which extends from the partition B to one side of the box. The larger compartment is provided with an aperture in the bottom, near its center, through which the stuff is forced by a pump into the box beneath the float F, which rests upon the surface of the stuff. The partition B does not extend so high as the sides of the box. Consequently, if more stuff is forced into the box after it is filled to a level with the top of partition B, the stuff will escape by gravity over the partition into the two smaller com-

partments, each of which is provided with an escape opening in the bottom, the opening D leading to the paper-machine, and the opening E leading back to the reservoir from which the stuff is pumped into the box. The thickness and weight of the paper manufactured depends upon the amount and quality of stuff delivered to the machine in a given time. As uniformity in the paper is essential, and uniformity in the quality of the stuff is not subject to absolute control, we must control the amount. The object to be obtained, therefore, is to cause the variations in the quality of the stuff to produce corresponding variations in the amount of supply. This has been approximately accomplished heretofore in various ways by means of valves and sliding gates operated by an attendant, and by balances and by floats.

I employ a gate, G, supported by the sliding rod H. The lower end of the gate rests against the upper side of partition B, and compels the stuff escaping from the box to flow through the narrow openings on either side of the gate. The sliding rod H is connected with the float F, so that the one acts upon the other by means of the levers I and J, shaft K, and upright L.

When the stuff being delivered into the box from any cause changes in density or quality—for example, becomes thicker—it becomes necessary (since the pump supplies a constant quantity) to diminish the supply going to the machine and let the surplus escape, which is done by the action of the float upon the gate in the following manner: The thicker stuff does not run so freely over the partition B and dams up, as it were, until the pressure is sufficient to force the same quantity over the partition. This damming up causes the surface of the stuff in the box to assume a higher level and raise the float. As the float rises it acts upon the levers and shaft before mentioned, and causes the rod H to slide to the left, or toward the opening which leads to the machine. The sliding rod carries with it the gate, which narrows the outlet to the machine and widens the opening through which the surplus escapes. When the stuff in the box becomes thinner it flows over the partition more easily, the level is reduced, the float falls with the surface of the stuff, and the relative size of the

outlets changes to increase the supply to the machine. It is evident, therefore, that any variation in the thickness of the stuff acts to regulate the supply before any part of it can reach the machine.

5 T is a discharging-gate provided with handle U, by which it can be raised, sliding in supports O, attached to the partition B, so as to leave open the aperture N in the lower side 10 of the partition, through which the box may be emptied when not in use or when desired.

Having thus described generally the purpose and manner of regulating the stuff in paper-machines and the operation of my machine as 15 a whole, I will now explain more fully the relation and operation of the improved parts.

I am aware that floats have been heretofore employed to act by means of a disk or wheel and levers upon a movable gate to vary the 20 size of the outlets. I prefer to dispense with the disk or any equivalent thereof and apply the power from the float to move the rod H, which supports the gate G. I am thus enabled to adjust by means of the thumb-screws P P' 25 the gate to any desired position upon the sliding rod, and in this way secure exact control of the weight of the paper by varying the position of the gate upon the rod.

The lever I may be slotted to admit the end 30 of rod H and work against pins in the rod; or the rod may be slotted to receive the levers. The frame which supports the shaft K is vertically adjustable by set-screw Q. By raising or lowering the shaft, thereby lengthening or 35 shortening the lever I, the variations in the outlets from the stuff-box may be increased or diminished, as desired.

The position of the gate to make paper of different weights may also be varied by 40 securing lever J to upright L at various distances from the float, or by adjusting the gate in different positions upon the sliding support H, or in both ways. As heretofore constructed floats have been made rectangular 45 in form, which prevents their acting quickly to rise and fall with the stuff on which they rest, due in a measure to the adhesion of the thick stuff to the sides of the float.

I have ascertained by long experiment that 50 the best form for a stuff-float is the form shown in the drawings, which is hollow and convexo-convex on the outside. It may be made solid, of some light substance, and convexo-plane, the plane surface being the upper 55 surface, and it may be of any suitable material, though I prefer copper. Such a float rides freely upon the surface of the stuff, and will even respond to the pulsations of the

pump, which facilitates the passage of the stuff through the outlets by agitating the gate. 60

The failure of all attempts to effectually regulate the flow of stuff in paper-machines by means of floats has been largely due to the width of the outlets, which were left the same as in the ordinary stuff-boxes. If the outlets 65 are made narrow, variations in the thickness of the stuff will produce greater variations in the height of the surface of the stuff in the box than they would if the outlets were wider. Consequently the float is more sensibly and 70 effectually acted upon by slight variations in the quality of the stuff. I prefer to make them narrower by inserting the angular-shaped pieces R R in the stuff-box, although it may be done by making the box itself narrower at 75 one end or side. There may also be adjustable slides S, sliding on rod M, to vary the width of the outlets, one for each outlet. By constructing the box so that the inside of the same shall be narrower on the side containing 80 the outlets there is a greater agitation of the stuff on that side, caused by the inward flow from the pump. Settling of the heavier portions of the stuff in front of the gate and outlets is almost wholly prevented, and the stuff 85 is more evenly mixed at the verge of the outlets.

What I claim as new, and desire to secure by Letters Patent, is—

1. In combination with a paper-machine 90 stuff-box, a float, F, suitably-connected arms or levers, I and J, and sliding rod H, supporting a gate, G, substantially as described, and for the purposes set forth.

2. In a paper-machine, a stuff-regulating 95 float, convexed substantially as described, and for the purposes set forth.

3. A paper-machine stuff-box contracted as to its inner dimensions on the side from which the contents are discharged, substantially as 100 described, and for the purposes set forth.

4. In a paper-machine stuff-box, a regulating-gate adjustable upon a sliding support, substantially as described, and for the purposes set forth. 105

5. In a paper-machine stuff-box, the partition B, provided with a discharge-opening, N, in combination with a gate, T, substantially as described, and for the purposes set forth.

In testimony whereof I have hereunto set 110 my hand this 12th day of March, 1883.

CORNELIUS YOUNG.
